UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

AUTOMATIC RIBBON-REVERSE.

1,385,547.

Specification of Letters Patent. Patented July 26, 1921.

Application filed January 20, 1919. Serial No. 272,002.

To all whom it may concern:

Be it known that I, Otto A. HOKANSON, a citizen of the United States, residing at Woodstock, in the county of McHenry and 5 State of Illinois, have invented certain new and useful Improvements in an Automatic Ribbon-Reverse, of which the following is a specification.

This invention relates to typewriters, but 10 more particularly to the means for feeding and automatically reversing the direction of feed of the typewriter ribbon. The principal object of the invention is to provide a new and improved construction of 15 this kind which is simple, durable and inexpensive in construction, effective and efficient in operation.

The invention consists in the novel construction, combination and arrangement of 20 the several parts.

In the accompanying drawings—

Figure 1 is a plan view with some of the parts broken away for clearness, of a mechanism constructed in accordance with the 25 principles of this invention; Fig. 2 is a detail of the reversing shaft holding means; Fig. 3 is a sectional view of one of the ribbon spools and feeding and reversing means applied thereto; Fig. 4 is an enlarged view 30 of one of the reversing wheels and levers; Figs. 5 and 6 are side and plan views respectively of the preferred form of reversing wheel and the lever operated thereby; Fig. 7 is a view of a modification; Fig. 8 is a 35 side elevation of a part of the operating mechanism therefor; Fig. 9 is a perspective of one of the operating parts; and Fig. 10 is a detail of the connection with the universal bar.

40 In the present type of automatic ribbon reverse there is a shaft 1 extending transversely of the machine and supported by depending portions 2 of the frame or top plate 3 of the typewriter. This shaft is longitudinally movable into either one of 45 two positions determined by the grooves 4 in which the shaft is held by the spring pressed pawl 5, as shown in Fig. 2.

Above the shaft 1 is a reciprocable universal bar 6 adapted to be engaged by the type bars in their movement to the printing point in the well known manner, and attached to the universal bar is a supporting frame 7 which carries a perforated lug 8 55 through the perforation of which extends a

pin 9 which projects from an arm 10 secured to the shaft 1. This pin 9 is of such a length that it will permit the longitudinal movement of the shaft to either of its positions without becoming disengaged from the 60 perforated lug 8. The oscillation of the universal bar and its frame 7 causes a corresponding oscillation of the shaft 1 each time the universal bar is engaged because of the connection of the pin 9 with the universal 65 bar frame, and this oscillation of the shaft is utilized for feeding the ribbon.

At each side of the machine and adjacent the ends of the shaft 1 is a vertically extending ribbon spool shaft 11 which carries 70 a ratchet wheel 12 below the top plate 3. Mounted on the shaft opposite each ribbon spool is a collar 13 which carries an upright arm 14 to which a feeding pawl 15 is loosely attached by the pivot 16, this end of the 75 pawl preferably having a slot 17 through which the shaft extends and the arm 14 being formed with a rounded projection 18 against which the end of the pawl 15 bears, this end of the pawl being preferably in the 80 shape of a right angle, as shown by Fig. 3, so that the pawl will rock about the pivot 16 and upon the rounded projection 18 as the shaft 1 is reciprocated longitudinally. This feeding pawl 15 is held against a supporting pin 19 which extends from the top 85 plate 3 and between the ears 20 of a holding pawl 21 which is pivoted by means of the ears upon the pin 19. One end of the holding pawl 21 is adapted to engage its ribbon 90 spool ratchet 12 and the other end 22 is engaged by an offset portion 23 of the arm 14 which is attached to the collar 13 so that the oscillation of the shaft about its axis does not affect the holding pawl 21, but the 95 longitudinal movement of the shaft controls the engagement of the pawl with its ratchet wheel. The ratchet pawl 15 is formed with ears 24 between the shaft 1 and the supporting pin 19 to which a spring 25 is attached, and a spring 26 is attached to one of the ears 20 of the holding pawl 21, both springs being attached to a suitable 100 pin or projection 27 which extends from the frame or top plate 3. The spring 26 tends to press the holding pawl 21 against the offset 23 and into engagement with its ratchet wheel and the spring 25 tends to hold the pawl 15 against the supporting pin 19, when the reversing shaft is in one 110

position, and the holding and feeding pawls at one end thereof, are in engagement with the corresponding ratchet wheel and the pawls at the other end of the shaft are held 5 out of engagement with the other ratchet wheel, as clearly shown in Fig. 1. The oscillation of the shaft about its axis causes the movement of both feeding pawls 15 but only one of them is effective as the other 10 one is out of engagement with its ratchet wheel.

Each ribbon spool shaft 11 is formed with a recess 28 communicating with a bore 29 at the lower end in which a rod 30 is longitudinally movable, the upper end of the rod being bent at right angles out of the recess 28 and having an extremity 31 which extends loosely through a perforation 32 in a lever 33 pivoted to swing about an axis at right 20 angles to the ribbon spool shaft and to the bent extremity 31. This lever is adapted to extend upwardly through a perforation or slot 34 in the bottom of a ribbon spool 35 and the upper end of the lever is engaged 25 by the ribbon 36 as it is wound about either spool, thereupon drawing up the lever which draws up the rod 30 to its uppermost position. The lowermost end of the rod which extends below the ribbon spool ratchet wheel 30 carries a toothed wheel 37 which is affixed to the rod in any suitable manner, as by means of a nut 38, and the toothed wheel, of course, rotates in either direction with the ribbon spool shaft. In its uppermost position, in which it is held whenever the ribbon 35 is wound around the lever or trigger 33, this toothed wheel 37 is free from engagement but when the spool becomes empty, the rod 30 falls due to its weight and the wheel 37 40 engages a toothed end 39 of a lever 40 which is pivoted between the ribbon spool shaft and the shaft 1 on a pivot 41, the other end of the lever having a projection 42 which engages with a segmental slot 43 near the 45 end of the shaft 1, the segmental slot or recess 43 being sufficient in extent to permit the oscillation of the shaft 1 about its axis without effecting the lever 40.

Instead of having a simple toothed wheel, 50 as shown by Fig. 4, a form, as shown by Figs. 5 and 6, may be adopted in which a toothed wheel 44 is attached to the end of the rod 30 of which the teeth 45 extend downwardly around the edge thereof. These 55 teeth are engaged by an upwardly extending tooth 46 on a lever 47, the width of this tooth being such that as the wheel 44 is rotated, this end of the lever 47 will swing clear of engagement with the wheel. This is also 60 the case with the other construction, as shown by the dotted outline in Fig. 4.

In operation, the ribbon is wound upon either one of the spools, depending upon the position of the reversing shaft 1 and as 65 the ribbon is wound upon one of the spools

due to the oscillation of the shaft 1 about its axis, because of its connection with the universal bar, the ribbon is unwound from the other ribbon spool until it is empty. As soon as the ribbon is unwound from engagement with the lever 33 on the empty spool, the rod 30 drops of its own weight, moving the toothed wheel at the bottom of the rod into engagement with the tooth of the reversing lever for its ribbon spool. If 70 it should happen that the tooth on the wheel 37 or 44 should engage on top of the tooth of the corresponding lever 40 or 47, the continued rotation of the empty spool will soon bring the teeth of the wheel 37 or 44 into 75 engagement with the tooth of its reversing lever and the continued rotation of the empty spool as it is pulled around by the ribbon from the full spool will cause the lateral movement of the reversing lever 80 which will shift the shaft 1 in an endwise direction, thereby throwing the pawls out of engagement with the full spool ratchet wheel and into engagement with the ratchet wheel of the empty spool. It will be ob- 85 served that the rotation of the toothed wheel 37 and 44, which is necessary to effect the operative action of the reversing lever, is very small so that the reversing action can readily be made to occur before the ribbon 90 is entirely unwound from the empty spool. This is of great advantage in preventing the stretching of the ribbon or writing of several characters upon the same place in the ribbon 95 near the ends thereof, due to the reversing 100 action.

It is also common practice to assist the reversing action of the shaft by providing one of the levers 40 with an angular extension 48 which is engaged by a spring-pressed holding pawl 49 which, as the reversing shaft is partially moved by either one of the reversing levers 40, passes over the tip of the angular extension 48 and assists in completing the action of the reversing lever be- 110 cause of its spring pressure.

Instead of employing a single bar for both reversing and feeding the ribbon, a reversing bar 50, as shown in Fig. 7, may be surrounded by a sleeve 51, the sleeve being rotatable 115 and the reversing bar 50 being longitudinally movable. The sleeve 51 is connected to an oscillating universal bar 52 by means of an arm 53, and at each end of the sleeve is a feeding pawl 54 connected to an arm 120 55 and adapted to engage one of the ribbon spool ratchet wheels 12'. A holding pawl 56 is also provided adjacent the feeding pawl and they are provided with tongues 57 and 58 respectively which are connected by 125 a spring 59 to hold them in engagement with the ratchet wheel. Each ribbon spool shaft 60 is provided with a pulley 61 and a gear 62, and connected to the ratchet wheel 12' is a gear 63 disposed adjacent the other 130

gear 62, but separate therefrom so that the ratchet wheel 12' and the gear 63 are moved separately and continuously by the action of its feeding pawl 54 due, of course, to the 5 oscillation of the sleeve 51.

Mounted on a stud 64 at each end of the bar 50 is a lever 65 one end of which is connected at 66 to the bar, and the other end of which carries a pinion 67 which is 10 adapted to mesh with the gears 62 and 63 at the same time when the lever 65 is moved in position so that the pinions will engage the gears. This, of course, will cause the gear 63, which is always rotated step by 15 step, to drive the gear 62 which is attached to the ribbon spool shaft 60 and thereby to wind the ribbon.

Also, pivoted on the stud 64 is an operating member 68 which has an arm 69 adapted to be engaged by the pulley 61 which is carried by the shaft 60. This shaft 60 is similar in construction and operation to the shaft 30 shown in Fig. 3 which has a trigger 33 at its upper end controlled by the amount 20 of ribbon wound upon the spool. The operating member 68 has another arm 70 which carries a pin or projection 71 which is adapted to be moved from the position shown in Fig. 8 downwardly with the shaft 60 and 25 with the other arm 69 until the pin 71 is engaged between the teeth of the uppermost gear 63, as indicated in Fig. 7. The continued rotation of the wheel 12' will cause the rotation of the member 68 to the dotted 30 line position shown in Fig. 7 which will broadly rotate the lever 65 about its pivot until its pinion 67 is brought into engagement with the gears 62 and 63. This action, of course, moves the reversing bar 50 longitudinally, and the reversing action is assisted by 35 means of the spring-pressed bell crank 49 and the angular extremity 48 of the lever 65, as previously explained.

In the operation of this construction it will 40 be obvious therefore that when the ribbon is unwinding from one of the spools, as shown by Fig. 7, the release of the trigger 33, as shown in Fig. 3, will cause the operating member 68 to drop, carrying the pin 45 71 in engagement with the gear 63 which by its continued rotation will move the member 68 and the lever 65 to reverse the bar 50 and to bring the driving pinion 67 into engagement with the gears 62 and 63. This, 50 of course, will cause the ribbon to be wound up upon the ribbon spool which has just been emptied and will cause it to be unwound from the ribbon spool at the other end of the bar 50, which is not shown in Fig. 7. Thus the 55 bar 50 acts only as the reversing bar and the sleeve 51 is always connected by means of its feeding pawls 54 with both of the ratchet wheels 12'.

I claim:

60 1. The combination with ribbon spools

and feeding means therefor, of a reverser comprising a longitudinally movable shaft which is oscillated about its axis during the ribbon feeding movement, and means controlled by the ribbon to move the shaft 70 longitudinally to reverse the ribbon feed.

2. The combination with ribbon spools and feeding means therefor, of a reverser comprising a longitudinally movable shaft which is oscillated about its axis during the ribbon 75 feeding movement, and means controlled by the ribbon on the emptying spool for reversing the position of the shaft.

3. The combination with ribbon spools and means for turning either one of them, 80 said means comprising a longitudinally movable shaft oscillatable about its axis and a feed reverser including said shaft, a lever in connection with the shaft at each end thereof, and means acted upon by the ribbon for engaging one of said levers when its ribbon spool is empty to reverse the longitudinal position of the said shaft.

4. The combination with rotatable ribbon spools, of feeding means and a reverser 90 therefor comprising a shaft oscillatable about its axis for selectively turning one of the ribbon spools in the ribbon feeding movement and longitudinally adjustable into either of two positions for reversing the 95 ribbon feed.

5. The combination with rotatable ribbon spools and feeding pawls therefor, of means for reversing the ribbon feed, said means including a longitudinally movable shaft 100 which is also oscillatable about its axis for actuating the feeding means, and the shaft also being provided with means for moving the said feeding means into and out of feeding engagement with respect to the ribbon spools due to the longitudinal shifting movement of the shaft.

6. The combination with a pair of rotatable ribbon spools and feeding ratchet wheels therefor, of pawls for engaging the 110 said wheels, an oscillatable shaft for moving said pawls in feeding the ribbon and longitudinally movable to throw the pawls for one ribbon spool into engagement with the feeding ratchet wheel thereof and the other 115 pawls out of engagement with the other ribbon spool ratchet wheel, and means in connection with the shaft and engageable when one ribbon spool is empty for moving the shaft longitudinally due to the feeding 120 movement of the shaft itself upon the opposite ribbon spool.

7. The combination with a pair of ribbon spools and a ratchet wheel for each spool, of means for selectively feeding one of the ribbon spools and for automatically reversing the ribbon feed, said means comprising a shaft longitudinally movable into one of 125 two positions for reversing the feed and axially oscillatable in effecting feeding 130

movement, and means brought into operation when one ribbon spool is empty for utilizing the oscillation of the shaft in effecting the feeding movement of the other ribbon spool for moving the shaft longitudinally into reversing position.

8. In an automatic ribbon reverse, a rotatable ribbon spool having a shaft with a ratchet wheel thereon, and a hollow portion at the lower end of the shaft, a lever below the shaft having an engageable tooth, a rod mounted for movement in the hollow portion of said shaft with a toothed wheel carried thereby at the lower end of the rod adapted to engage the tooth of the said lever when the rod is lowered, and an operating lever engaging the upper end of the said rod to move it up and down and to move the toothed wheel thereof into and out of engagement with the tooth of the said lever, the operating lever being engaged by the ribbon wound about the spool shaft to raise the rod and its gear out of engagement, the lever and the rod dropping by their own weight when ribbon is unwound from the lever.

9. The combination with a pair of ribbon spools and a ratchet wheel for each spool, of ratchet pawls for each of the said wheels, feeding and reversing means for said ribbon spools comprising a shaft oscillatable about its own axis to move the feeding pawls in unison and longitudinally movable into either one of two positions for throwing the feeding pawls of one ratchet wheel into engagement and the feeding pawls of the other ratchet wheel out of engagement with their respective wheels, and means for automatically reversing the position of the shaft when one ribbon spool is empty comprising a lever connected to each end of the shaft and extending below one of the ribbon spools, and means longitudinally movable to engage the lever and rotatable to move the lever laterally when the ribbon spool is empty for moving the shaft longitudinally, and means for yieldingly holding the shaft in either one of its two positions.

10. The combination with a pair of ribbon spools and means for rotating them, of an oscillatable shaft longitudinally movable for reversing the ribbon feed, means depending upon the ribbon wound upon the spools for reversing the position of the shaft, said means comprising a lever at each end of the shaft with one end of the lever extending below the adjacent ribbon spool, the other

end of one of the levers being formed with an angular extremity, means depending upon the ribbon wound upon the spool for engaging the end of the lever for moving the shaft longitudinally, and a spring-pressed device for engaging the angular extremity of one of the said levers and tending to assist the reversing action thereof as the angular extremity passes over its central point.

11. In combination, a pair of ribbon spools, an oscillating shaft, pawls operated by said shaft and having driving connection with but a single one of said spools at a given time to selectively rotate said spools, a trigger connected with each of said spools and operated by the ribbon thereon, a separate device connected with each of said spools and controlled by the trigger thereon and movable into one position when ribbon is wound on said spool and into another position when said spool is empty, and means controlled by said device for altering the driving connection between said pawls and said spools to shift the driving operation from one of said spools to the other and thus reverse the movement of the ribbon on said spools.

12. In combination, a pair of ribbon spools, pawls for selectively driving said spools, separate means connected with each of said spools and controlled by the ribbon thereon for changing the operative connection between said pawls and said spools to shift the driving operation of said pawls from one of said spools to the other when one of said spools becomes empty, and a longitudinally movable shaft for causing the operative connection between one of said spools and its pawls to be changed whenever the operative connection between the other spool and its pawls is changed, said pawls being connected with said shaft to be operated thereby in different positions of longitudinal adjustment of said shaft.

13. The combination with a ribbon spool, of pawl and ratchet mechanism for rotating said spool, a shaft arranged to oscillate about its axis for actuating said pawl and ratchet mechanism, means for shifting said shaft longitudinally for reversing the direction of rotation of said spool, and a device controlled by the ribbon upon said spool for actuating said shifting means.

In testimony whereof I have signed my name to this specification on this 15th day of January, A. D. 1919.

OTTO A. HOKANSON.
